APPARATUS FOR PLUCKING FOWL

Oscar H. Crapo, Dartmouth, Mass.

Application June 4, 1936, Serial No. 83,416

3 Claims. (Cl. 17—11.1)

This invention relates to methods and devices for plucking feathers from fowl in the process of dressing the same for cooking and it has for its object to provide a process and apparatus of that character which can effectively be used in place of the slow and tedious hand plucking operations heretofore commonly employed.

Prior devices which have been proposed for the purpose have commonly employed gripping elements which clamp or grip the feathers, such as a movable pair of jaws, peripherally contacting rollers or the like, which are intended to grasp the feathers and pluck them by a movement of the clamping members, with gripped feathers, away from the body of the fowl. Such devices have had their limitations in that they are usually not only complicated and expensive to manufacture, but also their mode of operation has required the insertion of the feathers between the clamping or gripping elements in some way, frequently necessitating the use of feeding or suction means for the purpose, thereby not only adding to the clumsiness and cost of construction and maintenance of the devices but making them unreliable in operation.

It is an object of the present invention to provide a device of this character which effectively plucks the feathers of the fowl, including even the small pin feathers, without employing gripping or clamping elements of any sort and without requiring the use of feeding or suction means to insure insertion of the feathers within the device. To that end I have found that both the large feathers and the pin feathers can be plucked cleanly and quickly by striking the feathers at their bases near the skin with a plurality of rapidly moving strip elements applied in rapid succession against the feathers. As will appear, a device operating in accordance with my invention is extremely simple in construction, inexpensive to manufacture and rapid and effective in operation.

These and further objects and advantages of my invention will appear from a more detailed description thereof taken in connection with the accompanying drawing in which:

Fig. 1 is a perspective view of my device shown in use plucking the feathers from a chicken or other fowl;

Fig. 2 is a side elevation view of the device;

Fig. 3 is an end elevation view as seen looking from the left in Fig. 2;

Fig. 4 is a detail vertical section taken along the line 4—4 of Fig. 2;

Fig. 5 is a side elevation view showing a guard that may be used with my device; and

Fig. 6 is a vertical section indicating a modified way of securing the plucking strips to the discs.

As indicated in the drawing, the device consists of a pair of discs 1 and 2, the disc 2 being somewhat smaller than the disc 1 for a purpose to be described, and the disc 1 being secured in any suitable manner to the end of a shaft 3 of an electric motor 4 adapted to rotate the device. Extending between the discs for securing them in their relative positions indicated, coaxially of each other and of the shaft 3, are a plurality of stays 10, 11 and 12, each secured at opposite ends in the discs as indicated. Extending between the peripheries of the discs are a number of plucking strips 20, 21 and 22 which converge toward each other as they approach the disc 2 as a result of the difference in diameter of the discs. For a purpose which will appear, I preferably so mount the strips in the discs that the feather-engaging edges of the strips, indicated at 20a, 21a and 22a when the device rotates in the direction of arrow A, are at an inclination to the axis of rotation of the device so that they approach the feathers obliquely.

The discs 1 and 2, may be of metal, and are preferably formed with side edges bevelled slightly to conform to the taper of the truncated conical outline of the assembled device indicated in Fig. 2. The peripheries of the discs may be slotted, as indicated at 13 in Fig. 4, for countersinking the ends of the plucking strips. These slots are, of course, so relatively positioned around the peripheries of the discs as to receive the plucking strips in their relative positions indicated in the drawing, namely, with the strips at equal intervals about the peripheries of each disc but with the slots in one disc staggered relative to the slots of the other disc to provide the desired inclination of the strips.

The plucking strips may effectively be stamped from sheet metal and are preferably slightly flexible. I have found that if the leading edges 20a, 21a and 22a of the strips be sharpened somewhat a more effective plucking operation results without any danger of cutting the feathers off. Before inserting the ends of the strips in the slots of the discs they are given a slight longitudinal twist to make the opposite ends of the strips lie flat in the slots. After the strips have been inserted in their proper slots they may be spot welded in place.

The motor 4, on the shaft of which the assembled plucker is mounted, should preferably

be of one-eighth horsepower or more and should rotate at a high speed, such as around 1500 R. P. M. The motor is provided with some sort of handle 18 by which the device may be manually propelled during the plucking.

5 In plucking fowl in accordance with my invention, I first preferably semiscald the fowl by immersion in hot water at a temperature of around 130°, for the purpose of loosening the 10 feathers and raising them from the body of the bird. As I have found that moisture on the feathers assists in the operation of plucking the feathers with my device, I then immediately pluck the feathers before they have had a chance 15 to dry.

10 The manner of using my device is obvious from Fig. 1 of the drawing, and, as there indicated, the fowl is laid on the table and grasped in one hand while the plucking device traverses the body of the fowl close to the skin to remove the 20 feathers as indicated. Whereas the device is illustrated as being moved against the grain of the feathers, I have found that this is of no great 25 consequence because an effective plucking operation results from moving the device with the grain of the feathers. In use it will be found that all of the feathers, including even the small pin feathers, are effectively plucked by the percussive movement of the rapidly moving strips 30 against the bases of the feathers.

30 The slight taper of the device formed by making the disc 2 smaller in diameter than the disc 1 is effective in working the device over the skin of the fowl in inaccessible areas such as under the wings and legs.

35 In using the device, I have found that the fowl is plucked more cleanly if the lowermost point of tangency of the rapidly moving strips is held fairly close to the base of the feathers and yet 40 care must be taken to guard against chafing or bruising of the skin of the fowl by direct contact of the strips therewith. To that end the device should be held at a slight distance, say one-quarter or one-eighth of an inch above the 45 skin. If desired, I may provide a guard to assist in gauging this distance and the guard may well be in the form indicated in Fig. 5 wherein I have shown a rod 50 secured at 51 to the housing of the motor 4 and reverse bent to provide a 50 guide portion 52 extending closely adjacent the path of movement of the strips. The guide rod 52 is rested against the skin of the fowl and by rolling the device over on the rod 52 the desired clearance can easily be maintained. As the pressure against the rod 52 may cause the rod to 55 engage the peripheries of the discs, I provide rollers 54 and 55 on the rod 52 to rotate with the discs.

60 While I have described the plucking strips 20, 21 and 22 as being secured in the peripheries of the discs 1 and 2, I do not mean to indicate thereby that the ends of the plucking strips are

exactly flush with the bevelled edges of the discs. Thus as indicated in Fig. 6, the peripheries of the discs may include a band 30, of the width shown, or even a much greater width, forced over the ends of the strips and the edges of the discs after 5 the strips have been inserted in the disc slots.

Obviously if desired my device may be provided with a suction hood for conducting away the feathers as they are plucked and instead of making it a manually operable and portable device 10 it may, by obvious modification, be mounted on a bench and the fowl to be plucked moved across the device. Regardless of how the plucking strips are secured in the discs, I prefer to dispose them at a slight inclination to the axis of the device, 15 as indicated, for I have found that the resultant oblique stroke against the feathers produces a somewhat gradual pull which draws the feathers more effectively than with the strips exactly parallel to the axis. My invention is not, however, to be limited to such details, except as indicated in the appended claims.

I claim:

1. A device for plucking fowl comprising a rotatable frame having strip means secured to its periphery and adapted to strike the feathers of the fowl with a rapid succession of percussions when the frame is rotated adjacent the skin of the fowl, the said strip means having non-cutting edges to pluck the feathers from the skin 30 without severing them said rotatable frame being formed with side edges beveled to conform to the taper of a truncated conical outline and said strip means lying within the boundaries of said outline and obliquely positioned relative to the axis of the frame, each strip means having one outer surface substantially in flush relation to the beveled edges.

2. A device for plucking fowl comprising a rotatable frame having strip means secured to its periphery and adapted to strike the feathers of the fowl with a rapid succession of percussions when the frame is rotated adjacent the skin of the fowl, the said strip means being spaced from the interior of the frame and obliquely disposed relative to the frame axis so that rotation of the frame directs the said strip means obliquely 40 against the feathers.

3. A device for plucking fowl comprising a rotatable frame having strip means secured to its periphery and adapted to strike the feathers of the fowl with a rapid succession of percussions when the frame is rotated adjacent the skin of the fowl, said rotatable frame being formed with tapered sides to conform to the taper of a truncated conical outline and said strip means being spaced from the interior of the frame so that the feathers can bend around the strip means when they are struck thereby and said strip means having non-cutting edges and being flexible to obviate bruising of the skin of the fowl.

OSCAR H. CRAPO.
